US00D851489S

(12) **United States Design Patent** (10) **Patent No.:** **US D851,489 S**
Zimak (45) **Date of Patent:** **** Jun. 18, 2019**

(54) **CANISTER**

(71) Applicant: **Gary Zimak**, Winnipeg (CA)

(72) Inventor: **Gary Zimak**, Winnipeg (CA)

(**) Term: **15 Years**

(21) Appl. No.: **29/572,602**

(22) Filed: **Jul. 28, 2016**

(30) **Foreign Application Priority Data**

Mar. 4, 2016 (CA) 167304

(57) **CLAIM**

The ornamental design for a canister, as shown and described.

DESCRIPTION

FIG. 1 is a top front perspective view of a canister showing my new design;

FIG. 2 is a bottom front perspective view thereof;

FIG. 3 is a right side elevation view thereof;

FIG. 4 is a left side elevation view thereof;

FIG. 5 is a front elevation view thereof;

FIG. 6 is a partial cross-section view along the line 6-6 in FIG. 5;

FIG. 7 is a rear elevation view thereof;

FIG. 8 is a top plan view thereof; and,

FIG. 9 is a bottom plan view thereof.

The dashed broken lines in the drawings illustrate portions of the canister that form no part of the claimed design.

The dot-dash broken lines in the drawings represent a boundary line that forms no part of the claimed design.

1 Claim, 5 Drawing Sheets
